US0D1107024S

(12) **United States Design Patent** (10) **Patent No.:** **US D1,107,024 S**
(45) **Date of Patent:** **** Dec. 23, 2025**

(54) **MOBILE COMPUTER**

(71) Applicant: **Hand Held Products, Inc.**, Charlotte, NC (US)

(72) Inventor: **Joanna G. Kucko**, Charlotte, NC (US)

(73) Assignee: **HAND HELD PRODUCTS, INC.**, Charlotte, NC (US)

(**) Term: **15 Years**

(21) Appl. No.: **29/825,797**

(22) Filed: **Feb. 4, 2022**

(51) LOC (15) Cl. **14-02**

(52) U.S. Cl.

USPC **D14/426**

(58) **Field of Classification Search**

USPC .. D14/138 G, 248, 341, 420, 421, 426, 427, D14/428, 453; D18/4.4-4.6

(57) **CLAIM**

The ornamental design for a mobile computer as shown and described.

DESCRIPTION

FIG. 1 is a perspective view of a mobile computer showing the new design;

FIG. 2 is another perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines illustrate portions of the mobile computer that form no part of the claimed design.

1 Claim, 6 Drawing Sheets
